FISHING LINE CASTING APPARATUS

Herman G. Lombard, Washington, D. C.; Pauline Lombard, executrix of said Herman G. Lombard, deceased, assignor to Julius Lombard, Washington, D. C.

Application October 18, 1955, Serial No. 541,203

5 Claims. (Cl. 124—20)

This invention relates in general to devices and apparatus for casting spinning lines such as fishing lines and similar cord, string or lightweight cable, or the like, in a wide range and variety of applications and uses.

Spinning is now commonly known as the method and means for casting a line from a reel having a stationary spool which allows the line to pay out freely over the end of the spool in uniform spiral-like convolutions. Conventional reels have spools that revolve as the line is taken off. The resistance of the revolving spool plus the starting friction thereof is not present in a spinning reel such that in using a spinning line, long easy casts are obtainable without possibility of backlash or snarling of the line which frequently takes place in a line on a revolving spool whenever the spool overruns the line's flow.

More particularly, the invention is directed to various improved forms of a compact, unitary combined hand spinning reel and sling type of catapult by which a spinning line wound on the reel is adapted to be cast by the sling over relatively long distances in a simple and easy hand operation without the use or need for a rod and the associated cumbersome auxiliary equipment, tackle or gear heretofore employed.

The invention, in any form, is one of general utility in that it is readily employed in many kinds of spin-fishing, spear fishing, hunting, etc., while also being usable as rescue equipment for casting a light line leading from a life line, or from a rope attached to a life buoy, or in casting a lead line for a tow rope to or from a disabled boat, as well as for casting a pilot line to a mooring rope or cable from or to a boat approaching a dock or pier to which it is to be secured. Various other uses of the invention will be apparent from the following disclosure, and accordingly, while the invention is described in connection with its use in fishing and related sports, it will be understood that the invention is not in any way limited to such use, but rather, is equally adaptable to many other applications and uses.

It is well known that in the sport of fishing, for example, the greatest pleasure and fun is enjoyed when it is possible to cast the bait or lure for long distances into a lake, stream or river. However, relatively few people have the skill and experience required for long casts with a rod and reel or by a twirling type of hand spinning reel in which the casting operation itself is very difficult to control and therefore dangerous not only to the user but also to bystanders and others nearby engaged in the same sport.

A primary object of this invention is to provide various forms of an improved spin-casting apparatus or device which comprises a combined spinning reel and sling type of catapult for projecting an object attached to a spinning line on the reel in a manner whereby the line easily spins from the reel for relatively long distances in a uniform linear path generally parallel to the central or longitudinal axis of the spinning reel. The casting operation requires but little skill or practice such that it is not unusual for a novice using the present invention to obtain casts equal

2

to and surpassing the distance cast by experienced anglers using the most expensive casting rods and reels.

The hand casting reel of the invention, in any form, is operable with ease, safety and high efficiency and accuracy by reason of the fact that the spinning line is subject to only minimum resistance as it spills off the stationary reel spool or drum under the pronounced force of the associated sling. A further object of the invention, therefore, is to provide an improved apparatus for casting a spinning line under force of a sling in a manner whereby the spinning line is easily cast considerable distances over a body of water such as a lake, river or stream, for example, and which apparatus is so simple and easily operated that excellent results are obtained when used by a novice as well as those skilled in the art of casting.

Another object of the invention is to provide various forms of casting reels such as described which comprise a compact, portable, hand operated apparatus that requires no rod nor arm motion or wide swinging area as when casting with a rod and reel. Inasmuch as any form of the invention requires only a simple hand operation in a minimum area, easy and highly accurate casting is possible from a sitting position in a row boat or canoe or in close quarters at the side of a crowded fishing vessel, river bank or bridge, as well as in areas where there are low hanging branches, brush or other obstacles.

A further object of the invention is to provide various forms of hand casting reels, as aforesaid, comprising a combined reel and sling type of catapult in a highly simplified inexpensive construction which is strong, durable and reliable and admirably suited for economical quantity production at relatively low cost.

Another object of the invention is to provide such casting reels embodying a sling type catapult defined by a pouch and elastic bands connected directly to the reel.

A further object of the invention is to provide an improved hand casting reel, as and for the purposes described, which is readily constructed at very low cost from standard metal or plastic tubing connected by a special joint in either a separable or permanent assembly of the tubing in a completed apparatus.

An additional object of the invention is to provide a similar hand casting reel in a highly simplified, low cost, one-piece construction which may be readily fabricated either as a one-piece metal stamping or as a one-piece cast metal or molded plastic article of manufacture.

Further objects and advantages, and other new and useful features in the construction, arrangement and general combination of elements and details of construction of the various improved forms of apparatus in accordance with the invention, will be readily apparent as the following description proceeds with reference to the accompanying drawings, for purposes of illustration but not of limitation, in which like reference characters designate like parts throughout, and in which:

Fig. 1 is a side elevational view, partly in section, showing one embodiment of a combined spinning reel and casting sling in accordance with the invention;

Fig. 1A is a side view of an alternate pouch which may be used in the sling employed in the apparatus of Fig. 1;

Fig. 2 is a view of Fig. 1 in front elevation and partly in section along line 2—2 of Fig. 1, and shows the apparatus as provided with an attachment for the related uses of spear fishing or shooting arrows, or the like; and,

Fig. 3 is a sectional view of Fig. 1, on an enlarged scale, taken on line 3—3, looking in the direction of the arrows, and shows the preferred doubled bands of the sling and the means for attaching the same in secured operative relation in the apparatus.

Fig. 4 is a side elevational view partly in section, showing a construction of the invention in a low-cost one-

piece metal stamping or as a one-piece cast metal or molded plastic article of manufacture; and,

Fig. 5 is a sectional view of Fig. 4, on an enlarged scale, taken on line 5—5 looking in the direction of the arrows, and illustrates an alternate type of band for the sling provided by a single thickness of elastic strip, and the means for attaching the same in a manner which may be employed in the apparatus of Fig. 1 and other forms of the invention.

Fig. 6 is a side elevational view of an apparatus similar to Fig. 4 which is provided with an outer rotary reel or spool, shown in section, for rewinding a spinning line thereon by rotating or turning said rotary reel or spool.

Fig. 7 is a front elevational view of another form of the invention comprising a fork type of support for the sling and a rotary reel or spool adapted to be turned for rewinding a spinning line thereon; and,

Fig. 8 is a sectional view of Fig. 7 on line 8—8 looking in the direction of the arrows.

Fig. 9 is a perspective view of a further form of the invention.

Fig. 10 is a perspective view of another embodiment of the invention.

Fig. 11 is a perspective view of an additional form of the invention.

Fig. 12 is a perspective view of still another embodiment of the invention.

Fig. 13 shows another form of the invention.

The various forms of the invention all embody the general construction and organization of a combined spinning reel and sling in a portable hand reel and hand operated apparatus wherein a body member defines said spinning reel or a mounting for a spinning reel at the forward side of said body member together with a sling at the rearward side of said body member adapted to cast or project an object attached to a spinning line on the reel in a long, lineal path generally parallel to the central or longitudinal axis of the reel. The action involved is in the nature of what may be termed "sling casting" and it is to be appreciated that such sling casting may be readily accomplished with the same accuracy as a slingshot which, of course, is highly desirable in instances where the spinning line must reach a specific location or target.

In the description which follows, it will be understood that the term "spinning reel" refers to any such reel in the form of a spool, drum, or pegs, or the like, on which a line may be wound and peeled therefrom in a series of uniform spiral-like convolutions which straighten out in a long lineal direction generally parallel to the central or longitudinal axis of the reel, as aforesaid.

Likewise, the term "sling" refers to any such catapult similar to a slingshot comprising elastic bands or metallic spring means, or any equivalent sling comprising a metal or other spring or spring arm, or the like, such as a bow similar to that in a bow and arrow apparatus, or a spring actuated plunger or piston in a cylinder telescoped within or otherwise defining a spinning reel, as will be readily understood from the present disclosure.

The term "object" refers to any object or article which is attached to the spinning line and projected by the sling, and thus indicates, for example, a weight, sinker, lure, bait, float, shaft, spear or other missile that is attached to the spinning line and projected by the sling in the manner of a slingshot to cast the spinning line in a long uniform lineal path, as aforesaid.

It is also to be understood that as respects any form of the invention in which a member or part is referred to as made of metal, the invention fully contemplates any similar or equivalent construction made of plastic, wood or other suitable material.

Referring now, more particularly, to the drawings, Fig. 1 shows one form of the invention in a highly simplified, low-cost construction which may be readily fabricated from standard commercial forms of plastic or metal.

tubing or stampings providing such tubing. Preferably, there is employed the inexpensive standard commercial tubing made of aluminum which provides an apparatus that is advantageously light in weight, strong, durable and corrosion resistant as is highly desirable in salt water areas.

In the example shown in Figs. 1 and 2, the body of the apparatus, designated generally 10, is provided by a section of large size tubing 12 which includes a portion defining an annular reel 14 in the form of a spool or drum, or the like. Preferably, the tubing 12 is formed with a circumferential depression defining said reel portion 14 between a bead or shoulder 15 at the rearward end thereof and an outwardly flared annular flange or bead 16 at the forward end thereof for retaining the line wound upon said reel 14. This large size tubing 12 is advantageously provided in a diameter of six or seven inches or so, such that approximately eighteen inches or more of line is contained in each convolution of the line rewound on the reel 14 which, of course, provides for a most desirable quick rewinding of the line in a minimum of time and effort.

A narrow V-shaped notch or kerf 17 is provided in the edge of said flange 16 at the most desirable location for preventing unintended peeling off of the line 18 wound upon the reel as shown in Fig. 1. Preferably such a notch 17 is formed in the flange 16 at each side of the reel to accommodate both right and left handed users and, if desired, a series of these kerfs or notches 17 may be provided for clipping the line 18 at any of several points. Such a kerf or notch 17 is used to secure the spinning line 18 on the reel 14 when not in use, and otherwise serves to hold a needed slack portion of the spinning line out of the way if necessary, preparatory to casting, but with an instantaneous release of said spinning line 18 in the casting operation without in any way restraining or impeding the flow of said spinning line 18.

Preferably, the terminal end of the spinning line 18 is provided by a length of heavier gauge line adapted to withstand the stresses of casting as well as frictional wear from sand and rocks. A slack portion is provided in the terminal end of the spinning line as illustrated in Fig. 1 and to this slack portion there are secured one or more hooks 20, a float 22, if desired, and a weight or sinker 24 on the extremity of said line 18, for example.

The body 10 including the reel 14 is connected to a smaller tube 30 defining a handle 31 for the apparatus. Preferably the handle 31 is hollow for storing extra hooks, weights and other equipment as illustrated in dotted lines in Fig. 1. The lower open end of the handle 31 is closed in any suitable way, as by a plastic or metal cap 33 or equivalent cork 33', Fig. 4. In the low cost construction of the present example, the tube 30 likewise is provided from standard commercial aluminum or plastic tubing and joined to the larger tube 12 in either a permanent or detachable connection provided by a hollow hub 34 drawn from the lower wall of said large tube 12. Such a hollow hub 34 is readily drawn from the aluminum material of said larger tube 12 and the interior thereof defines an advantageous cup-shaped receptacle serving as a temporary resting place for the sinker 24, as illustrated in dotted lines in Fig. 1, when the apparatus is carried about or prepared for a casting operation.

The exterior of said hollow hub 34 may be designed for either a separable or permanent joint or connection to the handle 31 defined by the small tube 30, as aforesaid. In a separable joint, said hollow hub 34 is designed for a close friction fit in the adjacent end of the tubular handle 31 to provide a connection which is tight and rigid but capable of separation when it is desired to detach the handle 31 from the body 10 to facilitate packaging in the smallest size container or for storing the apparatus in a tackle box, or glove compartment of an automobile, for example.

A permanent connection of the body 10, including the reel 14, to the handle 31 is readily obtained by swaging or welding the hollow hub 34 to the adjoining end of the tubular handle 31 or by employing an oversize core or plug 35, Fig. 2, for expanding said hollow hub 34 into a locked connection with said handle 31. The use of such a core or plug 35 is intended in either a separable or permanent connection as a member which seats in said hollow hub 34 and is provided with a socket 36 or equivalent stud for removably supporting a guide 38 which is employed in various other uses of the apparatus. In the present example, the guide 38 is shown in the form of a pin having a split lower end adapted to snap readily into and out of the socket 36. The upper end of said guide 38 is in the nature of a fork for supporting and guiding a pointed shaft, spear or arrow 39 to which the spinning line 18 is attached, as shown in Fig. 2, in the use of the apparatus for spear-fishing, hunting and surface fishing, or the like, by means of baited hooks attached to said shaft 39. The apparatus is otherwise usable with such a guide 38 for shooting a pointed spear or arrow 39, Fig. 2, in archery or target sports, etc., and in this relation, the spear or arrow is retrieved by the spinning line 18 when rewound on the reel 14 in the usual manner.

A sling 40 is attached to the large tube 12 to extend in operative position at the rearward side thereof for engaging the sinker 24 or other object attached to the spinning line 18 such as the spear or arrow 39, Fig. 2, and projecting said object 24 through said large tube 12 in a usual casting operation by which the spinning line 18 is peeled off of the reel 14 at high speed under the pronounced force of said sling 40. The sling 40 is similar in operation and use to that employed in a conventional slingshot and may be of any character suitable for the purposes just described. In the present example, a sling construction and arrangement is provided by a leather pouch 42, or the like, serving as what may be termed the engager for the object attached to said spinning line 18 and projected by the sling. The pouch or object engager 42 is provided with a hole or eyelet 44 at each end thereof for receiving a loop in either a single or doubled length of rubber strip 46, or the like, defining an elastic band connected to each end of said pouch 42. The loop in a band provided by a single length of rubber strip is bound or tied in the usual manner. In using a band composed of a doubled length of rubber strip, Fig. 3, the bight thereof defines a loop 48, Fig. 1, which may be connected in the holes 44 in the pouch 42 without need for binding said loop 48, thereby providing an important advantage and saving in this regard. The pouch 42 will not shift on the loops 48 if the holes or eyelets 44 thereof are provided in a width slightly smaller than the normal width of the doubled elastic strip 46 so that said doubled strip 46 is crimped edgewise in binding engagement with the edges of the holes 44 in a manner which prevents shifting of said pouch 42 in assembled relation with said loops 48. Such a loop 48 defined by the bight in a band 46 provided by a doubled strip of elastic may otherwise be knotted where it extends through the associated hole or eyelet 44 to positively secure the band to the pouch, if desired.

Likewise, a single or doubled strip of elastic defining said bands 46 may be connected to any other selected type of pouch or object engager. By way of example, Fig. 1A illustrates a pouch or object engager 50 in the form of a receptacle comprising substantially a cup, or the like, for holding a lure 51, baited hook, etc., employed as the object attached to the spinning line 18 and projected by the sling in a casting operation. In the present example, the well known "bucktail" is illustrated, in dotted lines, as such a lure comprising a hook concealed within a group of camouflaging strands. Such lures for spin fishing are usually especially weighted and

thereby adapted for casting in the same manner as with the sinker 24, Fig. 1, or by using the cup-shaped pouch or object engager 50, Fig. 1A, which advantageously guards against accidental contact with the hook concealed within the lure 51. The cup-shaped pouch 50, Fig. 1A, is provided in any suitable design to comprise a finger grip 52 on its closed end and holes or eyelets 54 at its forward end for attaching the bands 46 thereto substantially as described with reference to the pouch 42 shown in Fig. 1. Preferably the cup-shaped pouch 50, Fig. 1A, is provided with its lower inner wall 56 inclined downwardly and inwardly from the open end thereof as an added means for retaining the lure within said pouch or cup 50 preparatory to a casting operation.

A distinct subject of invention of equal importance to the invention in the general organization of the apparatus resides in the method and means for securing the forward ends of the single or double elastic bands 46 of the sling in operative connected relation to opposite side walls of the large tube 12 without tying or binding the ends of said single or doubled elastic bands 46, thereby obtaining considerable savings in this regard for cost of materials and time and labor for assembly. To this end, each side wall of the large tube 12 defining the body of the apparatus is provided with a slot or perforated area 60 of the general character shown in Fig. 1 comprising an assembling opening 62 in communication with a relatively narrower securing slit 64. The assembling opening 62 is of a size suitable for ready passage of the forward free ends of the doubled elastic band 46 while the securing slit 64 is of a width considerably narrower than the overall thickness of said doubled band 46. This overall thickness of the doubled band 46 is the combined thickness of two elastic strips forming said doubled band, as aforesaid, such that the same must be reduced in thickness, as presently to be described, in order to enter into said securing slit 64. The assembling opening 62 and securing slit 64, Fig. 1, are of a height substantially equal to or slightly less than the width of the doubled elastic band 46 and the perforated area or slot 60 is so arranged that the opening 62 may serve as a hole for binding or tying a looped portion of the band 46 therein in the event that the user prefers such a securing arrangement when a replacement band is installed.

In assembling and securing the forward end of an elastic band in accordance with this invention, the doubled band 46, for example, is passed through the assembling opening 62 from either inside or outside of the wall of the tube 12. Preferably the band 46 is passed through said opening from outside the wall of said tube 12 for most efficiency in the operation of the sling. The end of the band 46 is pulled through said assembling opening 62 until the remainder of the band extending to the pouch 42 is of the proper effective length. The band is then pulled simultaneously on opposite sides of the portion thereof in said opening 62 to stretch said portion as necessary to reduce the thickness thereof to a size thin enough to be slipped into the securing slit 64, as shown in Fig. 3. The band is then released and assumes its normal thickness except for the portion which is frictionally and gripingly compressed between the edges of said securing slit 64 in a manner which provides a positive fixed lock on the band in such secured position. The free end of the band 46 inside the wall of the tube is then twisted as necessary to pass the same back through the assembling opening 62 where said free end is neatly held close to the wall of the tube 12. Preferably said opening 62 is provided smaller in length than the width of the band 46, so that the free end of said band must be squeezed therethrough and thereby very effectively retained in said opening 62, with any excess end portion thereof being cut off to enhance the appearance of the completed assembly.

Figs. 4 and 5 include a showing of an alternate arrangement for retaining the free end of either a single or doubled elastic band and otherwise illustrate the similar

application and securing of the forward end of a band 46' provided from a single elastic strip in the same general manner described with reference to Fig. 3 as respects the doubled band 46. A similar slot or perforated area 60 is provided comprising an assembling opening 62 in communication with a narrower securing slit 64. A second, auxiliary opening 66, Figs. 4 and 5, in opposite spaced relation to the securing slit 64, serves as a means for receiving the free end of said band 46' beyond the securing slit 64 and retaining the same in said auxiliary opening 66 in a substantially straight flat formation. Fig. 6 includes a showing of a further arrangement in which the similar slot or perforated area 60' is provided in a smaller size by a circular assembling opening 62' leading to the securing slit 64' for either a single band 46', Fig. 5, or a doubled band 46, Fig. 3, with the free end of either band being twisted or return bent and inserted back into said circular assembling opening 62' in order to be retained therein substantially as described with reference to Figs. 1 and 3.

In the operation and use of the apparatus shown in Fig. 1 as a hand reel for sling casting a spinning line 18, the sinker 24 or other weighted object attached to the end of said spinning line 18, is held and engaged within the pouch 42 of the sling. The spinning line 18 is arranged to extend from said object 24 through the hollow body or tube 12 to a slack portion in front of the reel 14. On this slack portion of the spinning line 18, there are attached, as aforesaid, one or more hooks 20, a float 22 or lure, for example. The remainder of the spinning line 18 extending from said slack portion is wound upon the reel 14 in the usual manner and retained against accidental peeling from said reel 14 by clipping the line 18 in the kerf or notch 17 as shown in Fig. 1.

The apparatus is then ready for a sling casting operation in which the pouch 42 is pulled as desired to stretch and thereby tension the elastic bands 46, whereupon said pouch 42 is released to project the sinker 24 or other object through the hollow body or tube 12 under the pronounced force of said tensioned elastic bands 46. The operation is similar to the shooting of a slingshot and the projected force on the sinker 24 or other object attached to the spinning line 18 is such as to peel said spinning line 18 off of the reel 14 at great speed and with little resistance, as aforesaid, in a manner whereby long and accurate casts may be obtained in practically every operation of the apparatus. In the event that a cast is longer than desired, the length of the cast may be immediately limited and stopped simply by turning the apparatus so that the reel 14 is in a horizontal position from which the line 18 cannot spin off of said reel 14 in the projected direction of said line 18, whereupon the flow of the line is stopped instantaneously. After a casting operation, the line is rewound upon the reel 14 in the usual manner and arranged for another casting operation in a repetition of the foregoing described procedure.

The same general procedure is followed in the use of the apparatus for casting a lure 51 using a cup-shaped holder or pouch 50 as described with reference to Fig. 1A, or in projecting a pointed shaft, spear, arrow, or similar object 39 attached to the spinning line 18 as described with reference to Fig. 2. In this relation, the apparatus, Fig. 2, is provided with the plug or core 35 seated in the hollow hub 34 and having a socket 36 for a pin carrying a guide or rest 38 for said pointed shaft 39 or similar object preparatory to the shooting thereof in the same general manner as in the line casting operation just described.

Fig. 4 shows another form of the invention in which the apparatus 70 comprises a body and handle similar to that of Figs. 1 and 2 as provided in a one-piece article of manufacture that is particularly suited for economical quantity production at very low cost. This form of device may be readily fabricated as a one-piece molded plastic or cast or stamped metal article of manufacture.

In the example of Fig. 4, the article is shown as readily formed in a one-piece metal stamping, preferably from a blank of standard aluminum sheet stock from which a large tubular body portion 71 in the form of a ring or collar is drawn defining a reel, drum or spool 72 similar to that of Fig. 1. An annular peripheral flange 74 defined by the plane of the blank is provided for at one end of said reel 72 to present a rearward shoulder or bead for retaining the spinning line wound on the reel, and a similar outwardly flared flange 76 is formed on the forward end of said reel 72 together with a kerf or notch 78 for retaining the spinning line wound on the reel, as and for the purposes hereinbefore described. The blank is designed to include integral ears 80 bent normal to the plane of said rearward flange 74 and provided with slots or perforated areas 60 for securing either a single or doubled elastic band 46 to the apparatus as also previously described with reference to Figs. 3 and 5.

A similar tubular handle 82 is formed from an integral portion of the blank extending radially from the rearward flange 74 and including suitable side sections 84 adapted to be bent inwardly toward each other in a tubular formation a to define said tubular handle 82. Preferably the upper end of said tubular handle 82 is closed by a plug 86 wedged therein at a point spaced from the open end thereof to define an advantageous cup serving as a temporary resting place for the sinker 24 as and for the purposes described with reference to Fig. 1. The lower end of said tubular handle 82 may be closed by a plastic cap 33 as also shown in Fig. 1 or by an equivalent cork 33' as seen in Fig. 4, in a manner whereby said tubular handle 82, likewise, serves as a storing chamber for extra sinkers, hooks and other equipment as illustrated in dotted lines in Fig. 4. The apparatus thus provided, accordingly, involves the same general organization and arrangement as that described with reference to Figs. 1 and 2 and is used and operated in the same manner.

Fig. 6 shows another form of the invention in which the apparatus 90 comprises a structure similar to that of Figs. 1 or 4 and is provided with a rotary reel, drum or spool 92 adapted to be turned in rewinding the spinning line thereon in the manner of a conventional rotary winding reel. The reel or spool 92, of course, remains stationary during casting of the spinning line therefrom in the same manner described with reference to Fig. 1, but is turnable relatively to the body of the apparatus 90 for rewinding the line on the reel 92 without handling the line as many users of the apparatus would prefer. In the example of Fig. 6, a one piece body similar to that of Fig. 4 is shown employed in such a rotary reel arrangement. The drawn tubular body portion 71 is initially provided without the outward flare on the forward end thereof as shown in dotted lines in Fig. 6. The rotary reel, drum or spool member 92 is provided in a tubular formation corresponding to the outer contour of said tubular body portion 71 to fit snugly in assembled relation thereon and is formed with a rearward flange 94 of corresponding shape and an outwardly flared forward flange 96. The rotary reel, drum or spool member 92, thus provided, is telescoped in assembled relation on said tubular body portion 71 and the outer peripheral edge on said tubular body 71 then formed into an outwardly flared flange 98 in abutting relation to the forward flared flange 96 on the rotary reel, drum or spool member 92, to retain said reel 92 in assembled relation on the tubular body portion 71 in the completed apparatus but capable of turning in rotary relation to said tubular body portion 71.

The rotary reel, drum or spool member 92 is provided with a crank in any suitable way, as, for example, by an integral extension 100 projecting from the flared outer flange 96 thereof and provided with a rotatable knob or roller 102 serving as such a crank for said rotary reel member 92. The apparatus otherwise is shown provided with an integral handle 104 the same as that of Fig. 4, and similar integral ears 106 provided with the slots 60' comprising the circular assembling opening 62' and securing slits 64'.

for securing thereto the ends of either single or doubled elastic bands 46 or 46' as previously described.

Figs. 7 and 8 show another form of apparatus 110 in accordance with the invention which may be provided with either a fixed or rotary reel, drum or spool, as and for the purposes described with reference to Fig. 6. The members of this form of apparatus may, likewise, be made of metal, plastic or wood, or a combination of these materials. The apparatus is constructed from a plate-like body 112 of any of said materials to comprise a pair of spaced arms 114 defining a fork similar to a slingshot with a sling 116 having its elastic bands frictionally secured in spaced slits 118 in the ends of said spaced arms 114. The body 112 is provided with an enlarged central portion mounting either a separate or integral fixed or rotary reel, drum or spool 122 made of sheet metal, plastic or wood, together with a handle 120 which preferably is tubular and closed on its lower end with a cork 121 or a cap such as 33 in Fig. 1, or other suitable closure.

In a fixed construction of the reel, spool or drum 122 on the body 112, the body and reel may be provided as a low cost one-piece article of manufacture made of metal, plastic or wood, as aforesaid. In a construction comprising a rotary reel 122, as shown in Figs. 7 and 8, the body 112 is provided with a circular opening 123 defining a bearing for a reel 122 in the form of a drum having a base 124 at its forward end. In the present example, the reel 122 is made of sheet metal bent to define a base 124 and a tubular portion 126 having an outwardly flared flange 128 at its forward end, an intermediate annular bead or shoulder 130, and a collar 132 on its rearward end which initially extends axially of the reel in position to be assembled in said circular openings 123 in the body 112 as shown in dotted lines in Fig. 8. The collar 132 is then bent and formed into a flange engaging the rearward side of the body 112 adjacent the opening 123 therein in cooperation with the bead or shoulder 130 at the forward side of said body 112. The reel, drum or spool 122 is thereby secured in rotatable relation in said circular opening or bearing 123 in the body 112, and, to this end, there is provided a suitable crank in the form of a knob or roller 134 rotatably secured to the base 124 at the forward side of said reel, drum or spool 122. This form of the invention, otherwise, may be provided with any of the desirable features or elements disclosed with reference to the previously described forms of the invention for operation and use in the general manner described in connection with Figs. 1 and 2.

Fig. 9 shows a further form of apparatus 140 in accordance with the invention provided by a one-piece circular body 142 made of metal, plastic or wood together with a suitable handle 144. A sling 146 is attached to the circular body 142 in any suitable way, preferably by any of the slot arrangements previously described with reference to Figs. 3, 5 and 6. A group of winding pegs 148 are radially spaced on the circular body 142 in a manner to define a reel for winding a line thereon and allowing the same to peel off of said pegs 148 in the usual manner of a spinning line. A reel provided by a series of spaced pegs in this or any similar or related manner is advantageous in that a spinning line wound thereon dries in a relatively short period of time which, of course, helps in preserving the useful life of the line. In the present example, the arrangement is such that said pegs 148 provide essentially a tubular reel projecting from the forward side of said body 142 in concentric relation to the trajectory of an object propelled by the sling 146 along substantially the central or longitudinal axis of the reel defined by said pegs 148. The same general construction is readily provided in a one-piece stamping similarly to that of Fig. 4 in which relation the tubular body portion 71, Fig. 4, would be drawn as spaced circumferential sections which define or may be formed to provide a series of integral fingers similar to said pegs 148. This form of the invention, likewise, may be provided with any of the desirable features or

elements of the previously disclosed forms of the invention for application and use in the manner described with reference to Figs. 1 and 2.

Fig. 10 discloses another form of apparatus 150 in accordance with the invention in which the body 151 of the apparatus is provided to include spaced arms 152 defining a fork for a sling 154 in a construction similar to that described with reference to Figs. 7 and 8, together with a suitable handle 155 extending from an intermediate portion 156 of said body provided with pegs 158 defining a reel for a spinning line similarly to the peg-type of reel described with reference to Fig. 9. This form of the invention also may be provided with any of the desirable features or elements in the previously described forms of the invention for operation and use in the manner described with reference to Figs. 1 and 2.

Fig. 11 discloses a further form of apparatus 160 in accordance with the invention in which the body of the apparatus is provided by a tubular body member 161 of metal, plastic or wood defining a reel 162, spool or drum having a rearward base 164, if desired, together with a suitable handle 166. A sling in the form of a spring arm 168 is mounted in projecting relation to said reel or drum 162 in position to cast an object attached to the spinning line 18. Such a sling may be provided by a leaf spring or spring shaft made of any suitable spring metal or flexible wood, for instance. In the present example, the spring arm 168 is provided by a spring metal shaft having a threaded end portion secured in an aperture in the tubular body 161 by lock nuts 170 on said threaded end portion clamped against the adjacent inner and outer walls of said tubular body 161. On the outer free end of said spring arm 168, there is attached a cup-shaped receptacle 172 including a knob or finger grip 174 similar to that shown and described with reference to Fig. 1A, and which serves as a holder or engager for the sinker, lure or other object attached to the spinning line 18 and adapted to be projected by said spring arm 168 in a casting operation similar to that described with reference to Fig. 1. This form of the invention, otherwise, may be provided with any of the desirable features or elements in the previously described forms of the invention for operation and use in the manner described with reference to Figs. 1 and 2.

Fig. 12 discloses another form of apparatus 180 in accordance with the invention in which the body of the apparatus, likewise, is provided by a tubular metal, plastic or wood body member 182, open at both ends, and defining a reel 184 provided with a handle 186 together with a guide 188 supported on the lower inner wall at the rear of said tubular body member 182 in an arrangement similar to that shown and described with reference to Fig. 2. A sling similar to a bow and arrow construction is provided in operative relation to the reel 184 in position to engage a pointed shaft 190, spear or arrow attached to the spinning line 18 and supported on said guide 188 for a casting operation. In the present example, such a sling is shown provided by a pair of spring arms 192 made of spring metal or wood and having their inner ends attached to opposite side walls of the tubular body member 182 in any suitable manner or, for example, by providing said spring arms 192 with threaded end portions and securing the same in apertures in the side walls of said tubular body member 182 by lock nuts 194 threaded on said threaded end portions and clamped against the adjacent inner and outer wall portions of said tubular body member 182. A string 196 is attached to the outer free ends of said spring arms 192 to complete the sling for engaging the shaft, spear or arrow 190 and projecting the same in a casting operation similar to that described with reference to Figs. 1 and 2 for spear-fishing and hunting, etc. In surface fishing, or the like, the shaft 190 would be floatable and provided with hooks 198 attached to said shaft 190 and/or hooks 199

11

attached to the spinning line 18. This form of the invention also may be provided with any of the desirable features or elements in the previously described forms of the invention for operation and use in the manner described with reference to Figs. 1 and 2.

Fig. 13 shows another form of apparatus 200 in accordance with the invention comprising a body 202 provided by a cylinder, or the like, having a suitable rearward wall 204 integrally formed therewith or defined by a screw threaded cap, or similar closure. The forward tubular end of said cylinder 202 is telescoped within a reel 206 defined by a spool or drum having a base provided with a central opening to which the forward end of said cylinder 202 is concentrically connected either integrally or by a screw threaded or riveted connection, or the like. Within said cylinder 202 a sling is defined by a plunger 208 and actuating coil spring 210 therefor positioned on a slidable axial shaft 212 extending through a passage in said rearward wall 204 of said cylinder 202 and provided with a suitable knob or finger grip 214. The arrangement is such that the spinning line 18 is wound upon the reel 206 and prepared with a slack portion outside the reel carrying one or more hooks 216 and a sinker 24 or other object secured to the terminal end of said line 18 extending through the opening in the base of the reel 206 into the cylinder 202 where said sinker 24 rests against the plunger 208 preparatory to a casting operation.

In a casting operation, the cylinder 202 defines a handle for the apparatus as the knob or finger grip 214 is pulled to cause the plunger 208 to compress the coil spring 210 against the rearward end wall 204 of said cylinder 202 thereby tensioning said spring 210. When the knob or finger grip 214 is released, the compressed coil spring 210 expands instantaneously to provide a pronounced spring force on the plunger 208 which in turn projects the sinker 24 or other object in a casting operation substantially similar to that described with reference to Figs. 1 and 2. This form of the invention, likewise, may be provided with any of the desirable features or elements in the previously described forms of the invention for operation and use in the manner described with reference to Figs. 1 and 2.

While the invention has been described in detail with specific examples, such examples are intended as illustrations only, inasmuch as it will be apparent that other modifications in the construction, arrangement and general combination of parts, elements and new and different features in the various forms of the improved apparatus may be provided without departing from the spirit and scope of the invention. The present embodiments are therefore to be considered in all respects as illustrative and not restrictive, the scope of the invention being indicated by the appended claims rather than by the foregoing description, with all changes falling within the scope, meaning and range of equivalency of the claims intended to be embraced therein.

What is claimed and desired to be secured by United States Letters Patent is:

12

1. A casting apparatus comprising a handle, a body portion connected to the handle, said body portion comprising a cylindrical tube having a substantial length measured along its axis, a slingshot sling having its ends connected to said tube adjacent one edge thereof, the portion of the tube adjacent its other edge serving as a reel, and a coil of fishing line carried thereon, said line having one end tethered to the tube and a weight secured adjacent the other end of the line.

10 2. A casting apparatus as defined in claim 1, said handle being hollow and open at its lower end, and a removable closure for said open end.

15 3. A casting apparatus comprising a handle, a body portion connected to the handle, said body portion comprising a cylindrical tube having a substantial length measured along its axis, a slingshot sling having its ends connected to said tube adjacent one edge thereof, the portion of the tube adjacent its other edge having a rotatable tube mounted thereon to form a spinning reel, and a coil of fishing line on said reel, said line having one end secured to said reel and a weight secured adjacent its other end.

20 4. A casting apparatus comprising a handle, a body portion connected to the handle, said body portion comprising a cylindrical tube having a substantial length measured along its axis, projections extending from said tube, a slingshot sling having its ends connected to said projections, and a coil of fishing line carried on said tube, said line having one end tethered to the tube and a weight secured adjacent the other end of the line.

25 5. A casting apparatus comprising a handle, a body portion connected to the handle, said body portion comprising a cylindrical tube having a substantial length measured along its axis, projections extending from said tube, a slingshot sling having its ends connected to said projections, said cylindrical tube having a rotatable tube mounted thereon to form a spinning reel, and a coil of fishing line on said reel, said line having one end secured to said reel and a weight secured adjacent its other end.
